ATTORNEY.

UNITED STATES PATENT OFFICE.

ARTHUR C. STONE, OF PROVIDENCE, RHODE ISLAND.

DESIGN FOR A BROOCH, BUTTON, OR BUCKLE-PLATE.

No. 39,243.

Specification for Design.

Patented April 7, 1908.

Application filed February 13, 1908. Serial No. 415,759. Term of patent 3½ years.

To all whom it may concern:

Be it known that I, ARTHUR C. STONE, a citizen of the United States, residing at Providence, in the county of Providence and State of Rhode Island, have invented a certain new, original, and ornamental Design for a Brooch, Button, or Buckle-Plate, of which the following is a specification.

The figure is a plan view of a brooch, button or buckle plate showing my new design.

I claim,
The ornamental design for a brooch, button, or buckle plate, as shown.

ARTHUR C. STONE.
